IMPLANTABLE MEDICAL-ELECTRONIC CIRCUITRY

William M. Chardack, Buffalo, N.Y., assignor to
Medtronic, Inc., Minneapolis, Minn.

Filed Oct. 7, 1969, Ser. No. 19,444

Term of patent 14 years

Int. Cl. D24—02

U.S. Cl. D83—1

FIG. 1 is a front elevational view of implantable medical-electronic circuitry, showing my new design;
FIG. 2 is a right side elevational view thereof;
FIG. 3 is a left side elevational view thereof;
FIG. 4 is a bottom plan view thereof;
FIG. 5 is a top plan view thereof;
FIG. 6 is a rear elevational view thereof; and
FIG. 7 is a fragmentary cross-section taken on line 7—7 of FIG. 5.

I claim:

The ornamental design for implantable medical-electronic circuitry, as shown.
